DISPLAY RACK FOR FISHING LEADER SPOOLS

John M. Sweeney, Denver, Colo., assignor to Wright & McGill Company, Denver, Colo., a corporation of Colorado

Application November 5, 1956, Serial No. 43,666

Term of patent 14 years

(Cl. D80—9)

Fig. 1

In the drawing,

Fig. 1 is a perspective view of a display rack for fishing leader spools showing my new design, and

Fig. 2 is a top plan view thereof.

I claim:

The ornamental design for a display rack for fishing leader spools, as shown.
